(57) **CLAIM**

The ornamental design for a display screen or portion thereof with icon, as shown and described.

DESCRIPTION

FIG. 1 is a front view of a first embodiment of display screen or portion thereof with icon showing our new design; and, FIG. 2 is a front view of another embodiment of a display screen or portion thereof with icon.

The broken lines illustrate a display screen or portion thereof and form no part of the claimed design.

The solid black shading shown in the drawings illustrates a contrast in appearance.
